CLAIM

The ornamental design for a motorcycle phone mount, as shown and described.

DESCRIPTION

FIG. 1 is a top, front, and right side perspective view of a motorcycle phone mount embodying my new design; FIG. 2 is a bottom, rear, and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial and enlarged right side perspective view thereof for area 9 in FIG. 1;

FIG. 10 is a partial and enlarged bottom perspective view thereof for area 10 in FIG. 2;

FIG. 11 is a partial and enlarged rear perspective view thereof for area 11 in FIG. 2;

FIG. 12 is a partial and enlarged bottom perspective view thereof for area 12 in FIG. 2; and,

FIG. 13 is a partial and enlarged left side elevation view thereof for area 13 in FIG. 5.

The broken lines shown in the drawings are included for the purpose of illustrating portions of the motorcycle phone mount that form no part of the claimed design.
